The ornamental design for a pressure regulation device, as shown and described.

DESCRIPTION

FIG. 1 is a front perspective view of a pressure regulation device showing my new design;

FIG. 2 is a front elevation view of the pressure regulation device of FIG. 1;

FIG. 3 is a rear elevation view of the pressure regulation device of FIG. 1;

FIG. 4 is a right side view of the pressure regulation device of FIG. 1;

FIG. 5 is a left side view of the pressure regulation device of FIG. 1;

FIG. 6 is a top view of the pressure regulation device of FIG. 1; and,

FIG. 7 is a bottom view of the pressure regulation device of FIG. 1.

The broken lines shown in the drawings represent portions of the pressure regulation device that form no part of the claimed design.
